(57) **CLAIM**

The ornamental design for a “wall lamp”, as shown and described.

DESCRIPTION

FIG. 1 is a perspective view of a “wall lamp” showing the design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines (where present) in all FIGS. show portions of the wall lamp that illustrates environment that forms no part of the claimed design.

1 Claim, 4 Drawing Sheets
